(57) **CLAIM**

The ornamental design for a light fixture mounting plate, as shown and described.

DESCRIPTION

FIG. 1 is a front perspective view of a light fixture mounting plate depicting a new design;

FIG. 2 is a back perspective view thereof;

FIG. 3 is a front elevational view thereof;

FIG. 4 is a back elevational view thereof;

FIG. 5 is a right elevational view thereof;

FIG. 6 is a left elevational view thereof;

FIG. 7 is a top plan view thereof; and,

FIG. 8 is a bottom plan view thereof.

FIG. 9 is a second front perspective view thereof depicting environmental structure.

FIG. 10 is a third front perspective view thereof depicting alternative environmental structure.

FIGS. 11 is a fourth front perspective view thereof depicting alternative environmental structure; and,

FIG. 12 is a fifth front perspective view thereof depicting alternative environmental structure.

The broken lines in the drawings illustrate portions of the light fixture mounting plate and environmental structure which form no part of the claimed design.

1 Claim, 12 Drawing Sheets
